UNITED STATES PATENT OFFICE.

CHARLES D. SPRAGUE, OF MINNEAPOLIS, MINNESOTA, ASSIGNOR OF ONE-HALF TO OTTO Q. BECKWORTH, OF SAME PLACE.

DESIGN FOR A BADGE.

SPECIFICATION forming part of Design No. 28,781, dated June 7, 1898.

Application filed October 25, 1897. Serial No. 656,370. Term of patent 7 years.

To all whom it may concern:

Be it known that I, CHARLES D. SPRAGUE, a citizen of the United States, residing in the city of Minneapolis, county of Hennepin, and State of Minnesota, have invented and produced a new and original Design for a Badge, of which the following is a specification, reference being had to the accompanying drawings, forming a part thereof.

In the said drawings, Figure 1 is a view in front elevation, and Fig. 2 a view in side elevation, illustrating my design.

By reference to the said drawings it will be seen that the leading and material features of the design are a pair of human hands grasping a knotted rope. The design shown also comprises a disk-like body of considerably less diameter than the length of the sec-

tion of the rope, which disk-like body is formed with a raised marginal flange or rib. These parts are so disposed as to form the face of the badge. Badges with this design are especially intended for use by "Shriners," as being to them a suggestive symbol.

Having described my invention, what I claim as new, and desire to secure by Letters Patent of the United States, is—

The design for a badge, substantially as herein shown and described.

In testimony whereof I affix my signature in presence of two witnesses.

CHARLES D. SPRAGUE.

Witnesses:

L. C. ELMORE,
F. D. MERCHANT.
